CLAIM

The ornamental design for an emergency radio, as shown and described.

DESCRIPTION

FIG. 1 is a perspective view of an emergency radio showing my new design;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.

(Continued)

Broken lines in the drawings depict portions of the emergency radio that form no part of the claimed design.
